(57) **CLAIM**

The ornamental design for a portion of a slipper, as shown.

DESCRIPTION

FIG. 1 is a perspective view of the top, right side and front of a first embodiment of a slipper portion, wherein no claim is made to the sole, to the heart-shaped element on the slipper upper, or to the two spots on the upper along the line of attachment of the upper to the outsole at the front end of the slipper;

FIG. 2 is a top plan view of the first embodiment of the slipper portion;

FIG. 3 is a bottom plan view of the first embodiment of the slipper portion;

FIG. 4 is a front elevation view of the first embodiment of the slipper portion;

FIG. 5 is a rear elevation view of the first embodiment of the slipper portion;

FIG. 6 is a right side elevation view of the first embodiment of the slipper portion;

FIG. 7 is a left side elevation view of the first embodiment of the slipper portion;

FIG. 8 is a perspective view of the top, right side and front of a second embodiment of a slipper portion, wherein no claim is made to the sole, to the heart-shaped element on the slipper upper, or to the two spots on the upper along the line of attachment of the upper to the outsole at the front end of the slipper;

FIG. 9 is a top plan view of the second embodiment of the slipper portion;

FIG. 10 is a bottom plan view of the second embodiment of the slipper portion;

FIG. 11 is a front elevation view of the second embodiment of the slipper portion;

FIG. 12 is a rear elevation view of the second embodiment of the slipper portion;

FIG. 13 is a right side elevation view of the second embodiment of the slipper portion; and,

FIG. 14 is a left side elevation view of the second embodiment of the slipper portion.
